CLAIM

The ornamental design for a device for chilling liquid containers, as shown and described.

DESCRIPTION

FIG. 1 is a front, top and side perspective view of the device for chilling liquid containers showing my new design in the open condition;

FIG. 2 is a front elevational view thereof;

FIG. 3 is a rear elevational view thereof;

FIG. 4 is a side elevational view thereof;

FIG. 5 is a side elevational view thereof;

FIG. 6 is a top plan view thereof, the bottom view being a mirror image of the top view shown in FIG. 6; and, FIG. 7 is an elevational view thereof with the door open and showing the interior.

FIG. 1

FIG. 3

FIG. 2

FIG. 5

FIG. 4

FIG. 6

FIG. 7
